Atlys.

UNITED STATES PATENT OFFICE.

JOHN C. LIGGETT, OF NEW YORK, N. Y., ASSIGNOR TO POSTINDEX COMPANY, INC., OF BOSTON, MASSACHUSETTS, A CORPORATION OF MASSACHUSETTS.

ADJUSTABLE INDEX.

Application filed October 21, 1922. Serial No. 596,156.

To all whom it may concern:

Be it known that I, JOHN C. LIGGETT, a citizen of the United States, and a resident of New York, in the county and State 5 of New York, have invented an Improvement in Adjustable Indexes, of which the following description, in connection with the accompanying drawings, is a specification, like characters on the drawings representing like parts.

This invention aims to provide a novel and improved adjustable index of the class in which paper index slips are disposed edge to edge in guides in which they are 15 slidable transversely of the slips.

The invention will be best understood by reference to the following description, when taken in connection with the accompanying drawings of one specific embodiment thereof, while its scope will be more particularly 20 pointed out in the appended claims.

In the drawings:

Fig. 1 is a front elevation of a portion of an adjustable index exemplifying the 25 invention;

Fig. 2 is a sectional view on an enlarged scale on line 2—2 of Fig. 1;

Fig. 3 is a sectional view on an enlarged 30 scale on line 3—3 of Fig. 1;

Fig. 4 is a perspective view of a single index slip as it appears before being placed in the guides; and

Fig. 5 is a similar perspective view of a 35 double index slip.

Referring to the drawings, and to the embodiment of the invention which is illustrated for purposes of exemplification, there is shown a series of index slips 6, which may be single as shown in Fig. 4, or multiple as shown, for example, in Fig. 5.

The index slips are held in a frame, herein comprising a plate or panel 7, having two opposite marginal portions, which are bent to form inwardly directed flanges 8, 45 beneath or in back of which are channels 9 to receive the ends of the index slips, as shown in Fig. 3.

Heretofore in the use of indexes of this class, it has always been a problem to prevent the index slips from riding over one another, instead of always remaining with certainty edge to edge. Various expedients have been employed to overcome this difficulty, but even they are open to more or less 50 objection, as for example the use of cellul-

loid tubes into which the index slips are introduced. All of these difficulties are obviated by the provision of the index slip herein shown, which has a transversely curved cross-sectional formation, as clearly 60 shown in Fig. 2; that is to say, the strip as viewed in cross-section is concavo-convex. Initially, the height of the arc (as shown in dotted lines in Fig. 2) is somewhat greater than the height of the arc after the 65 slip has been introduced into the channel; that is to say, when the slip is in place, it constitutes a spring which is held under stress. This is advantageous for several reasons, among them being the fact that 70 it causes a frictional resistance to sliding movement of the slip in the frame, and the further fact that the edges of the slip are caused to press firmly against the front face of the back of the panel, and are thereby 75 prevented from riding over one another.

Herein, these advantageous results are enhanced by curving the slip longitudinally, as well as transversely. This is especially important in the case of very long slips, 80 as the slips are thereby caused to press firmly throughout their entire length against the panel. The initial longitudinal curvature of the strip is well illustrated in dotted lines in Fig. 3, from an examination of 85 which it should be evident that, when the ends of the slip are introduced into the panel and confined thereby, the slip will be under stress in each of the two ways described, thus doubly ensuring against accidental displacement of the slip in its 90 guides.

Usually the name or other data will be applied to the slip while the latter is flat, and generally before the slip is cut from a 95 large sheet, because it is most convenient to apply the data by means of a typewriter. So, also, before the large sheet is cut, and even before the data is applied, the sheet is treated to exclude moisture and dirt, as by 100 placing the sheet in a bath of thin collodion, and then drying the sheet. In practice, this coating has been applied so thinly that its presence can scarcely be detected. After the data has been applied to the slip, and the 105 latter has been given the described formation, it may be, and herein is, coated again on both sides with transparent protective material, such as collodion, although in most cases the one coating applied before 110

applying the data is sufficient. When the coating is dried, it serves not only to protect the surface of the paper from dirt, but, what is more important, it also excludes moisture from the paper, and thus tends to enhance and preserve its springlike characteristics.

Having thus described one embodiment of the invention, but without limiting myself thereto, what I claim and desire by Letters Patent to secure is:

1. An adjustable index comprising, in combination, a frame presenting front and rear guides, and a series of strips of paper disposed edge to edge, having a transversely curved formation and thereby constituting springs which are held under stress between said guides.

2. An adjustable index comprising, in combination, a series of index members disposed edge to edge, each comprising a strip of paper having an initial concavo-convex form transversely thereof, and a frame in which said strips are held under stress due to said form.

3. An adjustable index comprising, in combination, a series of index members disposed edge to edge, each comprising a strip of paper having an initial concavo-convex form transversely and longitudinally thereof, and a frame in which said strips are held under stress due to said form.

4. An adjustable index comprising, in combination, a frame presenting front and rear guides, and a series of strips of paper disposed edge to edge, having a transversely

curved formation and thereby constituting springs which are held under stress between said guides, said strips being coated with transparent material which protects the paper from foreign matter.

5. An adjustable index comprising, in combination, a frame presenting front and rear guides, and a series of strips of paper disposed edge to edge, having a transversely curved formation and thereby constituting springs which are held under stress between said guides, said strips being coated on both sides with material which excludes moisture from the paper.

6. An adjustable index comprising, in combination, a frame presenting front and rear guides, and a series of strips of paper disposed edge to edge, having a transversely curved formation and thereby constituting springs which are held under stress between said guides, said strips being coated with material which increases their resistance to bending.

7. An adjustable index comprising, in combination, a frame presenting front and rear guides, and a series of strips of paper disposed edge to edge, having a transversely curved formation and thereby constituting springs which are held under stress between said guides, said strips being coated with transparent material which excludes moisture from the paper and increases its resistance to bending.

In testimony whereof, I have signed my name to this specification.

JOHN C. LIGGETT.
